[57] CLAIM

The ornamental design for the television antenna, as shown and described.

DESCRIPTION

FIG. 1 is a top, front, left side perspective view of a television antenna showing our new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a left side elevational view thereof;

FIG. 7 is a right side elevational view thereof;

FIG. 8 is a top plan view of one of the receiver portions shown separately for clarity of illustration; and,

FIG. 9 is a bottom plan view of FIG. 8.

The receiver is partially shown in FIGS. 2-7 for ease of illustration. The screening of the receiver portion is shown partially in FIG. 8 for ease of illustration.
